UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

METHOD OF MAKING HALOGEN DERIVATIVES OF HYDROCARBONS.

1,306,472.

Specification of Letters Patent. Patented June 10, 1919.

No Drawing.

Application filed May 24, 1917. Serial No. 170,633.

To all whom it may concern:

Be it known that I, HERBERT H. Dow, a citizen of the United States, and a resident of Midland, county of Midland, and State of Michigan, have invented a new and useful Improvement in Methods of Making Halogen Derivatives of Hydrocarbons, of which the following is a specification, the principle of the invention being herein explained and the best mode in which I have contemplated applying that principle, so as to distinguish it from other inventions.

The object of the present invention is to provide a method for making a double halogen derivative, for instance, a monochlor-monobrom derivative of a hydrocarbon, with assurance that the derivative will have the desired constitution. At the same time, I greatly simplify and correspondingly reduce the expense of operation in making derivatives of this sort.

To the accomplishment of the foregoing and related ends, the invention then consists of the steps hereinafter fully described and particularly pointed out in the claims, it being understood that the following description discloses but one of various ways in which the principle of the invention may be carried out.

By way of illustration, I shall describe the application of my present improved method to the making of monochlor-monobromethane from ethylene. As a preliminary step, I bubble chlorin gas through liquid bromin at a predetermined temperature to give a definitely constituted vapor mixture, in the present instance one having equal portions of the two halogens named. Under normal pressure conditions, a temperature of 15-20 degrees centigrade will give a vapor mixture of the chlorin and bromin in equal portions. This mixture is then conducted in gaseous form to a chamber containing ethylene, with which it reacts directly to form the desired compound, in accordance with the following reaction:

It will be understood that I do not mean to limit application of my present improved method to the formation of this particular compound, nor is the specific method by which the halogenation of the hydrocarbon effected a part of the invention in hand.

In other words, with certain classes of hydrocarbons, of which benzol is an example, a catalyst will be necessary at this stage in the operation of the process. By utilizing, however, in the halogenation step a vapor mixture having the desired portions of each halogen, the reaction with the hydrocarbon involves the absorption of the halogens in the same proportion as they are present in such mixture. The simplicity of the procedure whereby the mixture is obtained obviously commends itself for a manufacturing operation, it being merely necessary to maintain a predetermined vapor tension by properly regulating the temperature of the bath of liquid bromin to get the desired gaseous mixture of the two halogens.

Other modes of applying the principle of my invention may be employed instead of the one explained, change being made as regards the process herein disclosed, provided the step or steps stated by any one of the following claims or the equivalent of such stated step or steps be employed.

I therefore particularly point out and distinctly claim as my invention:

1. The method of making a double halogen derivative of a hydrocarbon, which consists in mixing the vapors of two halogens in such combining proportions as to produce a reaction of both halogens with the hydrocarbon; and then treating the hydrocarbon with such mixture of halogen vapors.

2. The method of making a double halogen derivative of a hydrocarbon, which consists in bubbling the one of lower boiling point as a gas through the other of higher boiling point in the form of a liquid, at a predetermined temperature, whereby a vapor mixture is formed in such combining proportions as to produce a reaction of both halogens with the hydrocarbon; and then treating the hydrocarbon with such mixture of halogen vapors.

3. The method of making a double halogen derivative of a hydrocarbon, which consists in mixing chlorin and bromin vapors in such combining proportions as to produce a reaction of both halogens with the hydrocarbons; and then treating the hydrocarbon with such mixture of halogen vapors.

4. The method of making a double halogen derivative of a hydrocarbon, which consists in bubbling chlorin gas through

liquid bromin at a predetermined temperature, whereby a vapor mixture is formed in such combining proportions as to produce a reaction of both halogens with the hydro-
5 carbon; and then treating the hydrocarbon with such mixture of halogen vapors.

5. The method of making a double halogen derivative of a hydrocarbon, which consists in bubbling chlorin gas through liquid bromin at a temperature of 15°-20° centi-
10 grade, whereby a vapor mixture having equal portions of such halogens is formed; and then treating the hydrocarbon there-

with, whereby the mono-chlor-mono-brom derivative of such hydrocarbon is formed. 15

6. The method of making mono-chlor-mono-brom-ethane, which consists in bubbling chlorin gas through liquid bromin at a temperature of 15°-20° centigrade, whereby a vapor mixture having equal portions of such halogens is formed; and then treating ethylene with such mixture, whereby the desired mono-chlor-mono-brom-ethane is formed. 20

Signed by me, this 12th day of May, 1917. 25
HERBERT H. DOW.
